UNITED STATES PATENT OFFICE.

AUGUSTE LOUIS DE MÉRITEUS, OF PARIS, FRANCE.

ELEMENT FOR GALVANIC BATTERIES.

SPECIFICATION forming part of Letters Patent No. 496,743, dated May 2, 1893.

Application filed September 30, 1891. Serial No. 407,223. (No specimens.) Patented in France November 28, 1890, No. 209,850; in Germany December 9, 1890, No. 59,677; in Austria-Hungary April 7, 1891, No. 54,671; in Belgium May 22, 1891, No. 94,970; in Spain June 30, 1891, No. 12,119; in Italy June 30, 1891, No. 29,789, and in Brazil July 29, 1891, No. 1,260.

To all whom it may concern:

Be it known that I, AUGUSTE LOUIS DE MÉRITEUS, a citizen of the Republic of France, residing in Paris, France, have invented a 5 Powerful Element for Galvanic Batteries, (for which I have obtained a French patent, November 28, 1890, No. 209,850; a German patent, dated December 9, 1890, No. 59,677; Austro-Hungarian, No. 54,671, dated April 7, 10 1891; Belgian, No. 94,970, dated May 22, 1891; Spanish, No. 12,119, dated June 30, 1891; Italian, No. 29,789, dated June 30, 1891; Brazilian, No. 1,260, dated July 29, 1891,) of which the following is a specification.

15 This invention relates to the construction of a powerful element for galvanic batteries in which the hydrogen is mechanically eliminated and polarization is practically obviated by employing as the positive pole of the ele- 20 ment a couple acting continuously as herein- after explained. This couple constituting the positive pole of the element may be composed of two bodies of any description provided that they are not attackable or liable to be affected 25 by acids to the same degree. In this case the hydrogen produced upon the attackable metal (positive pole) of the couple is always driven to the unattackable body or electrode and the metal or body which is attackable or acted on 30 (by the acid in the element) forming the other electrode of the couple which forms the positive pole of the element is always free from hydrogen. The extremely small quantity of oxide resulting from the action of the acid 35 upon the attackable metal of the couple being reduced as fast as it is formed by the hydrogen proceeding from the negative pole of the battery. This hydrogen follows the same path as the hydrogen produced by the couple. 40 It passes at first to the metal or attackable electrode of the couple but it does not remain there; a portion of this hydrogen is instantaneously reduced by the oxide formed on the attackable metal and consequently does not 45 polarize this metal. The remainder of the hydrogen that is to say the greater part of it does not remain upon this metal. It is im- mediately carried away by the current closed upon itself of the couple forming the positive 50 pole and is entirely set free upon the inat-

tackable electrode of this couple. In order to obtain this result it is indispensable that the couple forming the positive pole acts continuously and presents surfaces formed by material susceptible to the action of the acid 55 of the element and other surfaces formed by material not acted on or attacked by the acids and on which the hydrogen may be set free. This is what has never been done since the origin of the voltaic pile. When Smee's bat- 60 tery was made with silver and platinum and after his time copper and platinum later still the elements of a couple were in fact pro- vided but the couple did not work. The hy- 65 gen escaped on the platinized surface as well. It remained there less than upon the copper or silver but polarization still took place. There was no surface on the positive plate which always remained absolutely free 70 from bubbles of hydrogen. The effect is dif- ferent in the element now under considera- 75 tion. The couple works constantly and pol- larization is completely obviated even in a short circuit.

In the foregoing statements I have assumed 75 that the liquid in the battery consists of water acidulated with sulphuric acid alone but nit- ric acid may be added if required. In this case the formation of hydrogen and of the salt 80 of the attackable metal takes place more vig- orously on the attackable metal of the couple. This salt capable of reducing part of the hy- 85 drogen proceeding from the zinc is formed in greater abundance the remainder of this hy- drogen being driven over to the platinum as before. The principal phenomenon is the si- multaneous polarization and depolarization 90 of the positive pole of the battery and the sec- ondary phenomenon is the mechanical elim- ination of the hydrogen on the platinum of this positive pole. This result is obtained as hereinafter more fully explained.

In order that my said invention may be 95 fully understood I shall now proceed more particularly to describe the same and for that purpose shall refer to the several figures on the annexed sheets of drawings the same letters of reference indicating corresponding parts in all the figures.

Figure 1 of the accompanying drawings rep- 100

resents in vertical section a galvanic cell or element constructed according to my invention and Figs. 2 and 3 represent the cell in horizontal and in transverse section respectively. Figs. 4 and 5 show the construction of the positive poles of the battery. Fig. 6 is a side view; Fig. 7, a transverse section, and Fig. 8 a plan of a battery composed of a number of elements.

10 This element is provided with a zinc plate Zn (Fig. 3). This plate slides, in the same way as a drawer, in grooves formed in two blocks A and B of ebonite, glass or other insulating material extending from the upper 15 to the lower part of the element. Two head plates Pb perforated with holes of from about three-sixteenths to three-eighths of an inch in diameter are applied to the blocks A so as to inclose the zinc plate between them. They 20 are secured in position by two elastic rubber rings x placed at the upper and lower ends of the element. This arrangement enables the zinc to be very readily removed and replaced. The lead plates may be platinized 25 on the outer sides only. In this case all the hydrogen gas escapes externally. The inner surfaces of the lead where the hydrogen of the couple forming the positive pole is produced and from which it is driven onto the external 30 platinum remain always free from this gas.

When the lead plates are platinized on both sides the platinum is removed from the inner surfaces or edges of the perforations. With this arrangement likewise the couple works 35 very satisfactorily. Two porous vessels V V are placed in the box or trough containing the element and are maintained filled with pure or undiluted sulphuric acid which filters slowly through the sides of the vessel and 40 maintains the liquid at the proper degree of acidulation.

In place of perforating the platinized lead plates with holes as represented in Fig. 1 vertical slots or slots inclined in any direction or 45 any other form of perforation may be employed.

Fig. 4 represents an arrangement which may be employed with advantage in practice. The platinized lead plate is cut into narrow bands 50 or strips connected by an uncut portion at one end and these strips are twisted in the form of a corkscrew or helix.

In order to eliminate the hydrogen more effectually the plates forming the positive pole 55 (negative electrode) may be provided with a number of holes of pyramidal or taper form the base or larger end being directed downward on the side presented to the zinc as represented in Fig. 5. The axes of these holes or 60 passages may be inclined at an angle of forty-five degrees or they may be inclined in a general way to the surface of the plate in such a manner as to provide a natural and easy way of escape for the gases. These holes form in 65 fact chimneys in which a current is formed by the action of the lead and platinum couple. This arrangement represented in elevation

and in transverse section in Fig. 5 enables a most powerful current to be obtained.

My invention further relates to certain details in the arrangement of a battery composed of a number of elements. A battery provided with these improved arrangements is illustrated in longitudinal elevation in Fig. 6, in transverse section in Fig. 7 and in horizontal section in Fig. 8. In this case a series of elements E formed as hereinbefore described is placed in a box or trough F divided into a corresponding number of compartments by non-water tight partitions s. These partitions slide in grooves r formed in the ebonite or other acid proof lining of the trough E being so arranged that the liquid is capable of spreading or flowing into every part of the trough notwithstanding the presence of the 85 separations or partitions s and thus enables the trough to be filled or emptied in one operation. A rubber tube t may be employed for this purpose. The partitions s may be perforated or they may be notched or cut 90 away at the sides or at the bottom as represented at e Fig. 7 in order to facilitate the passage of the liquid to all parts of the trough. By these means the manipulation of the trough is greatly facilitated. The elements of a battery thus constituted may be connected in tension without any material diminution in the voltage.

The divisions between the elements in a trough have heretofore been made with partitions which completely separate or prevent any communication between the liquids in the cells or elements and consequently cause complications in the manipulation of the battery. This trough is also provided with an 105 improved arrangement for making the connections consisting in obtaining the contact for the electrodes by means of cups g filled with mercury or with an amalgam composed of mercury, lead and tin or with any suitable 110 amalgam of a pasty nature. The electrodes of the elements are provided with hooks or wires Z, z which dip into the amalgam contained in the cups g which are arranged externally on one side of the trough F containing 115 the elements. By these means an excellent contact is obtained which obviates the necessity for employing screws, terminals, binding posts and the like. The amalgam is moreover completely protected from the action 120 of the gases and acids.

It is advantageous to arrange the cups g upon a movable support G capable of adjustment in a vertical direction. This support is arranged to slide upon suitable guides g' and 125 is capable of being fixed either in the elevated position for making contact and of being lowered for the purpose of breaking contact by means of a rotary cam T (Fig. 6) or other equivalent device. By these means the connections between the several elements of the battery are enabled to be opened or closed when required by one movement.

In the drawings the battery is represented

as being coupled in tension but it is evident that it may be as easily connected in quantity by means of the cups *g*.

I claim as my invention—

5 1. A positive pole of a battery, formed of lead combined with platinum, presenting leaden and platinum surfaces, as and for the purpose set forth.

10 2. An electric battery having a liquid wholly or mainly of dilute sulphuric acid and a positive pole of lead combined with platinum and presenting leaden and platinum surfaces, as and for the purpose described.

15 3. A positive pole of a battery consisting of plates of lead, partially platinized to present free leaden surfaces in opposition to the platinized surfaces, substantially as set forth.

20 4. The positive pole of a battery, consisting of plates of platinized lead perforated with holes or slots of any suitable form and presenting free leaden surfaces, substantially as set forth.

25 5. A battery consisting of a zinc plate, and one or more platinized lead plates forming a couple, and presenting free leaden surfaces, in combination with supports of insulating material to which are attached the lead plates and which are provided with grooves for the

zinc plate to enable the said zinc to be removed and replaced without touching the 30 platinized lead plates, all substantially as set forth.

6. A positive pole of a battery, composed of platinized lead plates forming a couple, the said plates being perforated with a number 35 of holes of pyramidal or taper form, the bases or larger ends of which are directed downward, and having their axes inclined at an angle of about forty-five degrees or other suitable angle relatively to the plate, substantially as set forth.

7. A battery consisting of a box or trough, a plurality of elements therein, in combination with cups for amalgam, wires connected to the elements, adapted to enter the amalgam, and a support for the said cups, the said support being adapted to be raised or lowered to open or close the circuit, substantially as set forth.

In testimony whereof I have signed my 50 name to this specification in the presence of two subscribing witnesses.

AUGUSTE LOUIS DE MÉRITEUS.

Correction in Letters Patent No. 496,743.

It is hereby certified that the name of the patentee in Letters Patent No. 496,743, granted May 2, 1893, for an improvement in "Elements for Galvanic Batteries," was erroneously written and printed "Auguste Louis de Mériteus," whereas said name should have been written and printed *Auguste Louis de Méritens*; and that the said Letters Patent should be read with this correction therein that the same may conform to the record of the case in the Patent Office.

Signed, countersigned, and sealed this 3d day of April, A. D. 1894.

[SEAL.]

JNO. M. REYNOLDS,
Assistant Secretary of the Interior.
